Primary Examiner — Catherine Tuttle(74) Attorney, Agent, or Firm — Doherty Wallace Pillsbury MurphyCLAIM

The ornamental design for a table tennis or ping pong table, as shown and described.

DESCRIPTION

FIG. 1 is a top view of the table;

FIG. 2 is a side view of the table; and,

FIG. 3 is an end view of the table.

The broken lines are included for the purpose of illustrating portions of the table tennis or ping pong table that form no part of the claimed design.
